CLARENCE A. GOURLAY, OF JAMAICA, NEW YORK.

COVER TABLE FOR TYPEWRITERS.

Application filed February 8, 1927. Serial No. 166,660.

This invention is a typewriter accessory and is particularly intended for use on the well known No. 6 Remington-Noiseless typewriter.

5 In this machine, the upper front shield is mounted on the forward portion of the frame of the machine and the upper type bar guide is spaced rearwardly therefrom an appreciable distance. Between these 10 parts and slightly below the level of the tops thereof, the type bars are positioned in diverging relation. The type bar movements are, therefore, exposed at the top of the machine and directly between the operator and the carriage. This is a disadvantage for numerous reasons. For example, it is essential to the proper functioning of a Noiseless machine that it be kept well lubricated, i. e., that all parts thereof carry a 15 liberal supply of oil. If this machine is lubricated with a liberal supply of oil, I have found that when the type actions are operated, oil is very apt to be thrown upwardly through the opening between the 20 front shield and the upper type bar guides and cause spattering of oil upon the sheet of paper in the carriage. It is therefore necessary in operating such a machine to lubricate it sparingly, particularly as regards 25 the type bar actions and there is a marked tendency to under lubricate these parts for the reasons specified. Furthermore, my experience has shown me that the open space 30 provided in this machine between the forward edge of the upper type bar guide and the front shield permits considerable noise 35 to come from the machine when in rapid operation.

With the foregoing in mind, the object of 40 the present invention is to provide a cover table for machines of the character described and to so construct such table that it will entirely cover and conceal the operations of the type bar actions to which I have 45 referred. When such a cover table is employed, my experience has shown that it should be lined throughout with a suitable sound deadening material and at such 50 points where it would contact with the front shield, the upper type bar guides or the frame of the machine, it should be provided with gaskets which will preclude rattling or

metallic sounds due to vibration between the related parts.

The cover table of this invention is preferably in the form of a sheet metal stamping, lined throughout with a sound deadening material and adapted to be fitted to the No. 6 Remington-Noiseless machine, so as to be held in place by the conventional parts of the machine. The table is made perfectly flat at its top and rests at its rear margin upon the upper type bar guides with a gasket interposed between these parts. Its forward edge extends below the front shield 55 of the machine, and a gasket is interposed between said marginal edge and the front shield, so that the parts will not directly contact and cause rattling when the machine 60 is in operation. The lateral portions of the table are bent downwardly to overlie the normally open space between the front shield and type bar guides and flanges are formed on these sides of the table to permit 65 it to be clamped in place.

By making the table perfectly flat on its top, it will serve as a convenient means for adjusting and alining papers in direct proximity to the carriage and there may be formed thereon a pointer or index character adapted to cooperate with the bail of the carriage when the bail is thrown forward as is frequently done when adjusting papers in the machine or making erasures on carbon copies. The bail is adapted to slide freely 80 over the face of the table if the machine is operated while the bail is in its retracted position and cam surfaces are formed upon the table to cooperate with the rolls of such bail, so that the parts will not jam.

The structure is simple and from a manufacturing standpoint may be economically produced. It will materially lessen the noise incident to operation of the machine by precluding the exit of sounds from the 95 interior thereof. The lining of the table will preclude vibration thereof and serves also to catch any oil that may be thrown up from the key actions. It is therefore possible to fully and properly lubricate a machine when the present invention is associated therewith as excess oil cannot possibly be thrown upon the papers in the carriage.

Features of the invention, other than those specified, will be apparent from the herein-after detailed description and claims, when read in conjunction with the accompanying drawing.

The accompanying drawings illustrate one practical embodiment of the invention, but the construction therein shown is to be understood as illustrative, only, and not as defining the limits of the invention.

Figure 1 is a perspective view of a No. 6 Remington-Noiseless typewriter, with which the present invention is shown as associated. In this view, the greater portion of the machine is shown in dotted lines, and only the front shield, the upper type bar guide and the cover table of this invention are illustrated in full lines.

Figure 2 is a perspective view of the cover table of this invention showing a portion of the cover table broken away to illustrate its sectional appearance and also showing the front shield and upper type bar guide of a conventional machine in cooperative relation with the table and in vertical section.

Figure 3 is a section on the line 3—3 of Figure 2.

Referring to the drawings, 1 designates the frame of a typewriter machine, here shown as a No. 6 Remington-Noiseless typewriter. This machine is well known to the art and is in wide application. It is not considered necessary to describe details of the machine other than in so far as necessary to render the present invention fully understood.

The machine shown in Figure 1 embodies the frame 1, carriage 2, a front shield 3, and an upper type bar guide 4, sometimes called in the trade the comb guide.

Associated with the carriage is the bail 5. This bail is longitudinally graduated to assist in spacing papers in the carriage and is equipped with rollers 6, which bear upon the paper when the bail is in normal position. The bail is, however, mounted for pivotal movement on arms which permit it to be retracted from the carriage roller when it is desired to adjust the papers in the machine or to make erasures in carbon copies. In the machine as now built, the bail is adapted to be drawn forward on its pivot connection referred to and to rest upon a small upstanding bracket mounted on the comb guide 4 and extending upwardly a sufficient distance to preclude the rolls from engaging with the comb guide if the carriage is moved laterally while the bail is retracted as stated.

In carrying out the present invention, I entirely dispense with this bracket as it is unnecessary when the present invention is employed in this machine.

It will be noted from Figure 2 that the front shield 3 is spaced forwardly of the comb guide 4 for an appreciable distance

and the type bar actions are mounted directly beneath this opening, so that in the conventional machine, they are visible as one looks down on the machine. Dust and dirt fall into the type actions through this opening and not infrequently erasers, pencils and other foreign materials fall into the action and unless immediately removed may cause damage thereto.

In accordance with the present invention, the opening to which I have referred is entirely closed by means of a cover table 7. This table may be in the form of a casting, if desired, but I find it thoroughly efficient and practical to employ a sheet metal stamping in this connection. The table 7 is formed with a perfectly flat top 8, the forward margin of which is adapted to underlie the rear edge of the front shield, while the rear margin of the table overlies the comb guide 4. The flat top 8 is of substantially segmental shape and at its radial edges is provided with depending sides 9 of sufficient depth to extend downwardly to the top of the frame 1. As shown in Figure 2, the forward portions of each side are adapted to extend within the front shield and at the lower edge of this extending portion is a laterally extending ear or flange 10 adapted to underlie the cast attaching lugs 11 of the front shield, as shown in Figure 1. The ears 10 are perforated to register with the perforations in the lugs 11, so that when the front shield is secured in place by conventional screws, these screws will pass through the perforations 12 in the ears 10 and clamp the cover table rigidly to the machine. If desired, each side 9 may have a forward extension 14 carrying a laterally extending ear 15 adapted to rest on the top of the corresponding attaching lug 16 of the comb guide, so that the screws for securing the comb guide to the frame may be passed through the ears 15 before extending through the lugs 16 and threading into the frame.

This latter construction is shown in Figure 2, but it is omitted from Figure 1 in the interest of clearance. It will be understood in this connection that the use of the ears 15 and the extensions 14 is optional and they may be omitted, as shown in Figure 1 if desired.

I wish to call particular attention to the fact that the entire interior of the cover table is lined with a sound absorbing material 17, such as felt, or the like. This serves to damp vibration and render the structure as noiseless as possible. It will be further noted that the lining 17 is carried over the forward edge of the cover table to form a gasket 18 between the table and that portion of the front shield which it underlies, so that there will be no metallic sounds resulting from vibration between

these parts. Similarly, the rear margin of the table is spaced above the comb guide by a relatively deep gasket 19. This gasket is of sufficient height to make the flat top 5 of the table substantially horizontal and further to space the table sufficiently above the comb guide as to preclude the type actions from striking against the table. This is desirable since, in practice, these actions 10 sometimes rebound to a point slightly above the plane of the top of the comb guides.

To seal the gasket 19, the rear edge of the table is preferably flanged downwardly as shown at 20, although in no case should 15 this flange be of sufficient depth to engage with the comb guide, since, if it did, relative vibration between these parts would cause rattling.

When the bail 5 is retracted, as hereinbefore stated, it is adapted to rest upon the flat top of the table. The roller 6 carried by said bail will extend somewhat below the top of the table when the carriage is centrally positioned and in order to preclude 25 binding when the carriage is moved with the bail in this position, the table is provided at each of its lateral edges with stamped out guide lugs 21, as shown best in Figures 2 and 3. These lugs are slightly inclined and 30 are positioned to be in the direct path of travel of the roller 6. Thus, if the carriage is moved with the bail in forward position, the rollers 6 will engage the lugs 21 and cause the bail to be slightly lifted to preclude binding or straightening on the parts. 35

In Figure 1, the index pointer 22 is shown as delineated on the table 7. This takes the place of and serves the same purpose as the indication found on the bracket in the conventional machine, that is to say, it facilitates the placement of the carriage.

The cover table of this invention can be readily and expeditiously associated with a Remington-Noiseless #6 machine as it is 45 only necessary to remove the few screws which hold the front shield and comb guide in place and to thereupon bring the cover table into position and reinsert the screws. This will firmly bind the parts together. It 50 will be apparent from the foregoing detailed description that the invention is of pronounced utility and merit. It precludes the falling of dirt or extraneous articles into the type actions, keeps the machine cleaner, 55 renders it less noisy, and allows it to be properly lubricated without fear of soiling paper in the machine. The construction may be economical to manufacture and when enameled to correspond with the remaining 60 portions of the machine which it cooperates, the device is aesthetic in appearance and materially adds to the appearance of the machine. The table, moreover, provides a convenient place to arrange papers immediately 65 prior to their insertion into the machine

and also precludes unauthorized persons from tampering with the type bar actions.

The foregoing description sets forth the invention in its preferred practical form, but the invention is to be understood as 70 fully commensurate with the appended claims.

It will be noted from Figure 2 that the sides 9 are provided at their lower edges with narrow laterally extending flanges 22. 75 These flanges are preferable, in practice, as they insure the complete covering of the opening in the top of the frame.

Having thus fully described the invention, what I claim as new and desire to secure by Letters Patent is:

1. A cover table for Noiseless typewriters embodying a flat plate of substantially segmental contour to overlie and conceal the opening between the front shield and the 85 comb guide of a Noiseless typewriter, with the forward margin of the plate extending beneath the rear margin of the front shield and with the rear margin of the plate overlying the comb guide, flanges formed at the 90 lateral edges of said plate and extending downwardly to the frame of the machine, attaching lugs formed on the side flanges and adapted to be secured to the machine by screws which secure conventional parts of 95 the machine to the frame of such machine, sound deadening lining covering the inner face of the plate and its flanges, and gaskets interposed between the plate and the front shield and the plate and the comb guide to 100 preclude rattling between the plate and these parts.

2. A cover table for Noiseless typewriters embodying a flat plate of substantially segmental contour to overlie and conceal the 105 opening between the front shield and the comb guide of a Noiseless typewriter, with the forward margin of the plate extending beneath the rear margin of the front shield and with the rear margin of the plate overlying the comb guide, flanges formed at the lateral edges of said plate and extending downwardly to the frame of the machine, attaching lugs formed on the side flanges and adapted to be secured to the machine by 110 screws which secure conventional parts of the machine to the frame of such machine, sound deadening lining covering the inner face of the plate and its flanges, gaskets interposed between the plate and the front shield and the plate and the comb guide to 115 preclude rattling between the plate and these parts.

3. A cover table for Noiseless typewriters embodying a flat plate of substantially seg- 120

125

mental contour to overlie and conceal the opening between the front shield and the comb guide of a Noiseless typewriter, with the forward margin of the plate extending beneath the rear margin of the front shield and with the rear margin of the plate overlying the comb guide, flanges formed at the lateral edges of said plate and extending downwardly to the frame of the machine, attaching lugs formed on the side flanges and adapted to be secured to the machine by screws which secure conventional parts of the machine to the frame of such machine, sound deadening lining covering the inner face of the plate and its flanges, and gaskets interposed between the plate and the front shield and the plate and the comb guide to preclude rattling between the plate and these parts, inclined guide lugs supported on and extending laterally from the plate and into the path of travel of the rollers of the carriage bail to preclude jamming of the rollers with the plate when the carriage is operated with the bail in retracted position, and an index marker on the plate adapted to cooperate with the graduated bail of the carriage to facilitate the positioning of the carriage when the bail is in retracted position.

4. A cover table for Noiseless typewriters embodying a flat plate of substantially segmental contour to overlie and conceal the opening between the front shield and the comb guide of a Noiseless typewriter, with the forward margin of the plate extending beneath the rear margin of the front shield and with the rear margin of the plate overlying the comb guide, flanges formed at the lateral edges of said plate and extending downwardly to the frame of the machine, attaching lugs formed on the side flanges and adapted to be secured to the machine by screws which secure conventional parts of

the machine to the frame of such machine, sound deadening lining covering the inner face of the plate and its flanges, gaskets interposed between the plate and the front shield and the plate and the comb guide to preclude rattling between the plate and these parts, inclined guide lugs supported on and extending laterally from the plate and into the path of travel of the rollers of the carriage bail to preclude jamming of the rollers with the plate when the carriage is operated with the bail in retracted position, and an index marker on the plate adapted to cooperate with the graduated bail of the carriage to facilitate the positioning of the carriage when the bail is in retracted position.

5. A typewriter accessory for Noiseless typewriters embodying a sheet metal stamping of substantially segmental contour to underlie at its outer margin, the inner margin of the front shield of the machine and at its inner margin to overlie the comb guide of such machine, side flanges at the lateral edges of the plate extending in a downward direction to the frame of the machine, laterally extending ears carried by the side flanges for securing the stamping to the machine, a gasket positioned on the upper surface and about the outer margin of the cover plate, a gasket extending along on the under side and adjacent the inner margin of said plate, and a sound deadening lining covering the under surface of said plate.

In testimony whereof I have signed the foregoing specification.

CLARENCE A. GOURLAY.
